UNITED STATES PATENT OFFICE.

ANTON C. PAULSON, OF FARGO, NORTH DAKOTA.

ANVIL-VISE.

1,385,268.

Specification of Letters Patent. Patented July 19, 1921.

Application filed December 20, 1920. Serial No. 431,979.

To all whom it may concern:

Be it known that I, ANTON C. PAULSON, a citizen of the United States, residing at Fargo, in the county of Cass and State of North Dakota, have invented certain new and useful Improvements in Anvil-Vises; and I do declare the following to be a full, clear, and exact description of the invention, such as will enable others skilled in the art to which it appertains to make and use the same.

This invention relates to an improved anvil vise or clamp and one object of the invention is to provide a vise or clamp so constructed that it may be connected with an anvil of a conventional construction, the body of the vise resting upon the upper face of the anvil and set-screws being provided for engaging the sides of the anvil and securely but releasably holding the vise in place.

Another object of the invention is to so construct the body portion of this vise that a plurality of sets of jaws may be carried by the body, one set of jaws moving transversely of the body and a second set including a cross bar which constitutes a stationary jaw and a movable jaw positioned beneath the stationary jaw and resting upon cams carried by the movable jaws which move transversely of the body so that this movable jaw which is positioned beneath the stationary jaw may be moved into and out of a clamping position by movement of the transversely moving jaws.

Another object of the invention is to so construct the cam elements and the movable jaw resting upon the cam elements that this movable jaw which is removable will be prevented from accidentally moving transversely from beneath the upper stationary jaw or cross-bar.

Another object of the invention is to so construct this vise that the cross-bar or relatively stationary jaw may be easily and quickly put in place or removed, and to further so construct the cam-operated jaw that it may be easily removed when desired.

Another object of the invention is to provide improved means for slidably connecting the transversely moving jaws with the body of the vise.

Another object of the invention is to so construct the transversely moving jaws that they may be operated by means of a common actuating screw which is in swivel connec-

tion with a neck extension of one jaw and passes through a threaded opening formed in an upstanding arm carried by a bar upon which the second jaw is mounted. 60

Another object of the invention is to provide an improved type of tool holder which includes a standard carried by the cross-bar or relatively stationary jaw and tool-gripping means at the upper free end of the standard. 65

Another object of the invention is to so construct the tool-holding means of the standard that the jaws forming part of the same will be yieldably held in a gripping position. 70

Another object of the invention is to provide an improved type of article holder adapted to be gripped between the transversely movable jaws, this article holder 75 having jaw sections loosely connected and limited in their movement away from each other.

Another object of the invention is to so construct this vise that the major portions 80 thereof may be formed by casting thus permitting the device to be easily and cheaply produced.

This invention is illustrated in the accompanying drawings, wherein:

Fig. 1 is a perspective view showing the improved vise in position for use with the cross-bar or stationary jaw in place.

Fig. 2 is a view similar to Fig. 1 showing the cross-bar and coöperating jaw removed 90 and the separate article engaging device in place between the horizontally or transversely moving jaws.

Fig. 3 is a perspective view of the vise removed from the anvil and having the 95 cross-bar and coöperating jaw removed therefrom.

Fig. 4 is a vertical sectional view taken along the line 4—4 of Fig. 1.

Fig. 5 is a vertical sectional view taken 100 along the line 5—5 of Fig. 4.

Fig. 6 is a perspective view of the body portion of the vise looking from the opposite end to that shown in Fig. 3.

Fig. 7 is a perspective view of the cam- 105 operated movable jaw.

Fig. 8 is a longitudinal sectional view through the work-holder shown in use in Fig. 2.

This improved anvil vise or clamp is pro- 110 vided with a body having side walls 1 and 2 which are connected by a web 3, the upper

portion of the wall 1 being provided with an opening 4 above the web 3 and this web being provided with a transversely extending slot 5 which communicates with an enlarged opening 6 formed in the wall 2. This opening 6 is deeper than the opening 4 as clearly shown in Fig. 6 and a collar 7 is provided about this opening 6 so that a wide bearing surface is provided. Arms 8 extend 10 upwardly from the side walls 1 and 2 and these arms are formed relatively thick as shown clearly in Figs. 3 and 6 and provided with open ended sockets 9. Set-screws 10 are passed through threaded openings 11 15 and extend into the sockets 9 so that a cross bar to be hereinafter described may be securely but releasably held in these sockets 9. Set-screws 12 are passed through threaded openings in the lower portions of the 20 side walls for engaging the side faces of the anvil indicated in dotted lines in Figs. 1 and 2. It will thus be seen that by means of the set-screws 12, the vise or clamp may be securely but releasably held upon the anvil 25 and may be readily removed when desired. This body portion is formed in a single casting and may thus be cheaply produced but at the same time will be very strong and durable.

30 The jaws 13 and 14 which are both movable jaws and are to move transversely of the body rest upon the web 3 and bridge the slot 5. The jaw 13 is cast integral with a carrier bar 15 as shown in Fig. 4 and is 35 provided with a neck extension 16 for slidably fitting into the opening 4 of the wall 1 thus providing means for assisting in guiding sliding movement of this jaw 13. The end of the carrier bar 15 is beveled as shown 40 at 17 and the web 3 is provided with a beveled face 18 at the inner end of the slot 5. This carrier bar extends through the slot 5 and opening 6 and rests upon the wide bearing formed by means of the collar 7 and at 45 its outer end; this carrier bar is provided with an upstanding arm 19 having a threaded opening 20 formed therein to receive the threaded actuating screw 21. This actuating screw 21 is provided with the usual turning bar 22 and at its inner end is provided 50 with a head 23 which fits into a socket 24 formed in the neck 25 of the jaw 14. Plates 26 are secured to the outer end of the neck 25 to hold the head 23 in the socket 24 and 55 thus provide a swivel connection between the actuating screw 21 and neck 25. It will thus be seen that when the actuating screw is rotated, one of the jaws will remain relatively stationary and the second will move 60 toward the relatively stationary jaw. In actual practice, one of the jaws will at times remain stationary and the second jaw will move, while at other times, this will be reversed and in some instances both jaws will 65 move. In any event, the two jaws will

eventually be brought into contacting relation with each other or in engagement with any article which may be positioned between the two jaws. By having the two jaws constructed as shown, the jaw 13 carrying the 70 bar 15 may first be put in place and the jaw 14 then put in place after which the actuating screw will be passed through the threaded opening 20 and the plates 26 put in place to connect the actuating screw with 75 the jaw 14.

In addition to the jaws 13 and 14, this vise is provided with a second set of jaws which instead of having relatively horizontal movement, will have relative vertical 80 movement. This second set of jaws is provided with a relatively stationary jaw in the form of a cross bar 27 which fits into the sockets 9 and will be releasably secured in place by means of the set-screws 10. A 85 relatively movable jaw 28 is positioned beneath the jaw or cross bar 27 and is provided with a depending flange 29 and with a cam block 30 which tapers downwardly as shown in the perspective view of Fig. 7. This cam 90 block has its converging faces provided with grooves 31 which are adapted to receive the ribs 32 formed upon the converging cam faces of the arms or cam elements 33 carried by the jaws 13 and 14. It will thus be seen 95 that when the jaw 28 is put in place beneath the stationary jaw or cross bar 27, its cam block will rest upon the cam elements 33 of the jaws 13 and 14 and when these jaws are moved transversely through the medium of the actuating screw 21, the movable jaw 28 will receive upward or downward movement according to the direction in which the two jaws 13 and 14 are moved. If these jaws are moving toward each other, the jaw 28 will be moved upwardly toward a clamping 100 position but if the jaws 13 and 14 are moving apart, the weight of the jaw 28 will cause it to move downwardly with the spreading of the two jaws 13 and 14.

110 In addition to constituting a stationary jaw, the cross bar 27 provides a base for a standard 34 which extends upwardly and is provided with a bent upper end portion 35 which extends horizontally and forms a neck 115 or arm having a head 35 at its free end. This head 35 forms a stationary jaw for a tool gripper and is provided with a recess which cooperates with a similar recess in a movable jaw 36 to form a socket 37 in which 120 a tool may be placed. Pins 38 extend from the jaw 35 through openings formed in the movable jaw 36 and each of these pins carries a spring 39 for engaging the movable jaw, nuts 40 being screwed upon the threaded end portions of these pins 38 so that the springs may be placed under compression and thus the movable jaw yieldably held in a clamping position. The pins 38 in addition to mounting the movable jaw and 130

springs, also serve as means for guiding movement of the movable jaw.

It is desired to provide means for holding articles between the jaws 13 and 14 and there has therefore been provided an article holder in the form of jaws 41 and 42 which have their contacting faces cut to provide recesses registering to form sockets 43. These sockets 43 are of different sizes so that a bolt or other similar article may be placed in a socket of a convenient size. The jaw 42 is provided with end extensions 44 which extend across the end of the jaw 41 and these arms or end extensions 44 are provided with slots or sockets 45 to receive the pins 46 which extend from the ends of the jaw 41. From an inspection of Fig. 8, it will be seen that the slots 45 are elongated thus permitting the pins to have movement in the slots when it is desired to move the jaw 41 out of contact with the jaw 42. At the same time, the jaw 41 is prevented from becoming entirely separated from the jaw 42.

When this device is in use, it will be placed upon the anvil as shown and an article such as a metal bar may be gripped between the jaws 13 and 14 and bent down through the slots 47. If so desired, the bar may be simply held between these two jaws and either cut or any other desired operation performed. If it is desired to form a head upon a metal rod, the rod will be passed through the usual opening provided in an anvil and will be passed up through the opening 48 in the carrier bar 15. The heated upper end portion of this rod will be positioned in one of the sockets 43 of the work holder shown in Fig. 8 and the two jaws 13 and 14 then brought into tight binding engagement with the work holder. A rivet head can then be formed by simply beating down the heated end of the rod. If it is desired to make use of the clamp having the jaws moving vertically, the cross bar 27 and movable jaw 28 will be put in place.

The article to be gripped will be placed between the movable jaw 28 and the stationary jaw or cross bar 27 and the actuating screw 21 then rotated to bring the jaws 13 and 14 toward each other. This will cause the movable jaw to be moved upwardly and the article will be securely gripped. When the actuating screw is rotated in the opposite direction, the jaws 13 and 14 will spread and the movable jaw will move downwardly from the stationary jaw or cross bar thus releasing the article. If it is desired to make use of the tool holder carried by the standard of this cross bar, the punch or other tool which it is desired to make use of will be placed in the socket 37 and will be held over the work which will be either gripped between the clamping jaws 13 and 14 or may be placed in the holder of Fig. 8. Of course, if so desired, the movable jaw could be left

in place and the device to be operated upon held by means of this jaw. When it is no longer desired to make use of this vise, the set-screws 12 will be released and the device can be bodily removed from the anvil. 70

It will thus be seen that there has been provided a vise so constructed that it can be easily and quickly put in place and further so constructed that most of the parts may be formed by casting. 75

I claim:

1. An anvil vise comprising a body having side walls and a connecting web intermediate the height of the side walls for resting upon the upper face of an anvil with the lower portions of the side walls engaging the sides of the anvil, the side walls having oppositely disposed openings intermediate the length of the body, a carriage bar slidable through said openings, a jaw rigid with said bar between the side walls, a separate jaw between the side walls having a neck extending through one of the openings, an arm extending from one end of said bar and having a threaded opening, an operating screw extending through the threaded opening and having swiveled connection with the neck of the separate jaw. 80 85

2. An anvil vise comprising a body having side walls and a connecting web intermediate the height of the side walls for resting upon the upper face of an anvil with the lower portions of the side walls engaging the sides of the anvil, the side walls having oppositely disposed openings intermediate the length of the body, and the web having a transversely extending slot extending from the opening of one wall to a point adjacent the second wall, a carriage bar 90 95 100 slidably mounted in the slot and extending through the openings, a jaw rigid with the bar between the side walls, a separate jaw between the side walls resting upon the web and bar, and an actuating screw having threaded engagement with the bar and swiveled connection with the separate jaw. 105

3. The structure of claim 2 having the carriage bar provided with a thickened end portion resting upon the web and positioned in the opening of one wall and having the rigid jaw integral therewith, the separate jaw having a neck positioned in the opening of the second wall, and the adjusting screw passing through a threaded opening 110 115 120 in an arm carried by the carriage bar and having swiveled connection with the neck.

4. An anvil vise comprising a body having side walls and a web connecting the walls, gripping jaws positioned between the walls above the web and movable toward and away from each other, cams carried by jaws, supports carried by the side walls, a cross bar carried by said supports and forming a stationary jaw, and a movable jaw 125 130 135

resting upon the cams and moving toward and away from the stationary jaw when the first mentioned jaws are moved.

5. The structure of claim 4 having the cross bar and movable jaw removable and the removable jaw held against moving transversely out of engagement with the cams when resting upon said cams.

6. The structure of claim 4 having the cams provided with converging faces and the movable jaw with a coöperating cam block engaging the converging faces of the cams, and provided with grooves receiving ribs carried by the cams to hold the movable jaw against moving transversely out of place.

7. An anvil vise comprising an anvil engaging body, gripping jaws movably carried by said body and having actuating means, a stationary jaw carried by said body, and a movable jaw in operative relation to the stationary jaw and moved toward and away from the stationary jaw through the medium of the first mentioned movable jaws.

25 8. The structure of claim 7 and cam elements carried by the first mentioned movable jaws and engaging the movable jaw coöperating with the stationary jaw for moving the same toward and away from the sta-

tionary jaw when the first mentioned movable jaws are moved toward and away from each other.

9. An anvil vise comprising an anvil engaging body, gripping jaws carried thereby and having actuating means, a cross bar 35 carried by said body, and an upstanding arm carried by said cross bar and having article holding means at its free end positioned above said gripping jaws.

10. The structure of claim 9 having the article holding means in the form of a stationary jaw carried by said arm, a movable jaw, supporting and guiding means for the movable jaw, and resilient means yieldably holding the movable jaw in a set position. 45

11. A holder for use in connection with a gripping device, said holder comprising jaws having contacting faces cut to provide recesses forming sockets when brought together, one of said jaws having end extensions having sockets formed therein, and pins extending from the end of the second jaw into the sockets of the end extensions of the first jaw to limit separation of the jaws. 50

In testimony whereof I have hereunto set 55 my hand.

ANTON C. PAULSON.
